United States Patent Office

Des. 195,522
Patented June 25, 1963

195,522

HANDED CASSEROLE

Jens H. Quistgaard, Lucerne, Switzerland, assignor to Dansk Ovenware, Inc., Great Neck, N.Y., a corporation of New York

Filed Nov. 30, 1962, Ser. No. 72,671

Term of patent 14 years

(Cl. D44—1)

FIG. 1.

FIG. 2.

FIG. 3.

FIG. 4.

FIG. 1 is a top plan view of a handled casserole showing my new design;

FIG. 2 is a side elevation thereof with the handle shown in end elevation;

FIG. 3 is a bottom plan view thereof; and

FIG. 4 is a side elevation thereof turned 90 degrees relative to FIG. 2.

I claim:

The ornamental design for a handled casserole, as shown.
